No. 634,714.

Patented Oct. 10, 1899.

E. ARMSTRONG & J. J. MULCONROY.

WATER FILTER.

(No Model.)

(Application filed Apr. 26, 1899.)

UNITED STATES PATENT OFFICE.

ERNEST ARMSTRONG, OF CAMDEN, NEW JERSEY, AND JAMES J. MULCONROY, OF PHILADELPHIA, PENNSYLVANIA, ASSIGNORS TO THE ROBERTS MANUFACTURING COMPANY, OF NEW JERSEY.

WATER-FILTER.

SPECIFICATION forming part of Letters Patent No. 634,714, dated October 10, 1899.

Application filed April 26, 1899. Serial No. 714,488. (No model.)

To all whom it may concern:

Be it known that we, ERNEST ARMSTRONG, residing in the city and county of Camden, State of New Jersey, and JAMES J. MULCONROY, residing in the city and county of Philadelphia, State of Pennsylvania, citizens of the United States, have invented a new and useful Improvement in Water-Filters, which improvement is fully set forth in the following specification and accompanying drawings.

Our invention consists of an improved construction of a water-filter, as will be herein-after fully described, and particularly pointed out in the claims.

Figure 1 represents, on an enlarged scale, a sectional view of the filter, the section being taken on line *a a*, Fig. 2. Fig. 2 represents a section on line *y y*, Fig. 1. Fig. 3 represents a side elevation of the scraping or cleaning device employed, the same being shown in detached position.

Similar letters of reference indicate corresponding parts in the figures.

Referring to the drawings, *A'* designates a filter consisting of a casing *B'*, which is of cylindrical or other shape and provided with the base *C'*, from which leads the valved outlet *D'*.

E' designates a removable top through which passes the tube *F'*, the latter being provided with the apertures *G'* along its length and discharging the filtered water from its lower portion *H'*, as will be explained.

J' designates a cylindrical or other shaped filtering block or body which is constructed of filtering material of any suitable construction, said block fitting tightly upon or being secured to the rotatable tube *F'*, so as to be rotated in unison therewith.

K' designates a washer of rubber or similar material located upon the base *C'* and adapted to support the filtering-block *J'*, so that only filtered water will flow through the orifice *H'*.

We provide means for locking the tube in a fixed position relative to the casing, said means conveniently consisting of a locking-nut *L*, supported upon the lower portion of the tube *F'*, the upper portion of said tube

being provided with the locking-nut *M*, which 50 engages the upper threaded portion *N*, to which latter the crank or handle *P* is adapted to be applied, as will be explained. It will be seen from the foregoing description that the nuts *L* and *M* serve to lock the tube in a 55 fixed position relative to the casing.

Q designates a strip of metal or similar stiff resilient material, on which is supported the scraper *R*, the latter having the outer portion covered with emery *S* or other similar material, which contacts with the outer periphery of the filtering block or body *J'*, as is evident.

The filter can be readily attached to a spigot *T*, if desired, by means of the coupling devices *U*, from which latter leads the connection or conduit *V* to the bottom of the filter-casing *B'*.

The operation is as follows: When it is desired to use the filter, it is connected with the spigot *T*, as will be understood from Fig. 1, wherefrom it will be apparent that when the valved outlet *D'* is open the water in its normal or unfiltered condition will flow through the filter around the filtering-block 75 without passing through the tube *F'*. If the valved opening *D'* be closed, the water will pass through the filtering block or body *J'* and thence through the openings *G'* into the pipe *F'* and out of the orifice *H'*, as indicated 80 by the arrows in Fig. 1, the water leaving the filter through the block or body *J* in a perfectly pure and filtered condition, as is evident.

When it is desired to clean the filter, the nuts *L* and *M* are loosened, the crank *P* placed in position, and the tube *F'* and the filter block or body *J'* connected thereto revolved in the direction of the arrow *a*, (seen in Fig. 2,) wherefrom it will be seen that the contact of the scraper or cleaning device *S* 85 with the outer periphery of the filter-block will effectually remove all the impurities therefrom, which latter can be readily withdrawn through the valved outlet *D'*. The filter block or body *J'* is ordinarily of mate-

rial of such porosity that when the valved opening *D'* is open the water will not flow through the orifice *H'*, although it will of 95

course be apparent that the same may be supplied with a valve, if desired. After the filter has been cleaned or purified the handle or crank T can be removed, if desired, the nuts L and M tightened, and the valved opening D' being closed the filter is ready for use again.

Having thus described our invention, what we claim as new, and desire to secure by Letters Patent, is—

1. In a filter, a casing, an upright rotatable tube passing therethrough and projecting beyond the ends thereof, said tube being closed at its upper end, open at its lower end and provided with apertures between the ends of the casing, locking-nuts upon the upper and

lower ends of said tube impinging against the ends of the casing for holding said tube immovable relative to said casing, a filter-body carried by said tube within the casing, and an inlet.

2. In a filter, a casing, an apertured tube passing therethrough and journaled therein, a filtering block or body mounted upon said tube, means for rotating said tube and body in unison and means for locking said tube in fixed position relative to said casing.

ERNEST ARMSTRONG.
JAMES J. MULCONROY.
